UNITED STATES PATENT OFFICE

156,132

DESIGN FOR A RACK

Nena Lewis, Campbell, Ohio

Application August 26, 1948, Serial No. 148,311

Term of patent 14 years

(Cl. D80—10)

To all whom it may concern:

Be it known that I, Nena Lewis, a citizen of the United States, residing at Campbell, in the county of Mahoning and State of Ohio, have invented a new, original, and ornamental Design for a Rack, of which the following is a specification, reference being had to the accompanying drawing forming a part thereof.

The figure is a perspective view of a rack, showing my new design.

I claim:

The ornamental design for a rack, as shown.

NENA LEWIS.
